(57) **CLAIM**

The ornamental design for a wheel keyring hook, as shown and described.

DESCRIPTION

FIG. 1 is a front-left perspective view of a wheel keyring hook showing my new design;

FIG. 2 is a front view of the wheel keyring hook of FIG. 1; FIG. 3 is a back view of the wheel keyring hook of FIG. 1; FIG. 4 is a left view of the wheel keyring hook of FIG. 1; FIG. 5 is a right view of the wheel keyring hook of FIG. 1; FIG. 6 is a top view of the wheel keyring hook of FIG. 1; and,

FIG. 7 is a bottom view of the wheel keyring hook of FIG. 1.

The broken lines shown in the drawings illustrate portions of the wheel keyring hook that form no part of the claimed design.

1 Claim, 5 Drawing Sheets
